Walter J. Pettingell

UNITED STATES PATENT OFFICE.

WALTER J. PETTINGELL, OF LOWELL, MASSACHUSETTS.

STATION-INDICATOR.

SPECIFICATION forming part of Letters Patent No. 319,505, dated June 9, 1885.

Application filed January 17, 1883. (No model.)

To all whom it may concern:

Be it known that I, WALTER J. PETTINGELL, a citizen of the United States, residing at Lowell, in the county of Middlesex and State of Massachusetts, have invented certain new and useful Improvements in Station-Indicators; and I do hereby declare that the same are fully described in the following specification, and illustrated in the accompanying drawings.

The object of this invention is to provide as a permanent fixture to the outside of cars, for the information and convenience of travelers, a train-directory denoting the various stopping-points in their order. This device, secured to the side of the car, is opened to expose the names of the stations before the train starts, and at each stopping-place the names of stations not yet reached are exposed and the names of those reached and passed are concealed.

My invention consists in a frame secured to the side of a car and inclosing a plate or series of plates on which the names of the several stations at which the train will stop are inscribed in their order, in combination with an adjustable shield adapted to be moved in grooves, so as to expose all or part of such names, or to conceal them all.

My invention also consists in the devices and combinations of devices set forth in the appended claims.

In the drawings, Figure 1 is a view in perspective showing my apparatus as applied to a car. Fig. 2 is a vertical central section of the same.

A is a frame, of any suitable form, fixed permanently to the outside of a car, and having an open front.

B is a movable shield fitted to run in grooves C in the frame, so that it may be adjusted to various positions. It is provided with a convenient locking device to secure it as desired.

E E represent placards or plates, of any suitable material, on which are severally inscribed the names of the various or the most prominent stations where the train or the particular car will stop. These station-plates,

hung one above another, are of uniform size 50 and made interchangeable, so that they may be placed in reverse order for the return trip or changed from time to time to indicate other stops, since the car may run alternately on a branch road or the main line, or be one trip 55 in an express and the next in an accommodation train. The plates E E are supported in any convenient way, so as to present the names of the stations in their order. They may be mounted on spring pins or hooks F, inserted 60 in the back G, each of sufficient length to receive several cards, one in front of another; or they may rest edgewise on ledges or shelves F', one above another, with means of holding the plates against displacement. Two or 65 more names may appear on a single plate. Additional plates may be carried in pockets above and below the front opening in the frame. Where a car is used regularly on a given train, making the same stops on each 70 round trip, two placards will be sufficient for all the names, one having them arranged in the order of the stops on the outward trip, and the other in the reverse order. The shield B may be a single inflexible piece running in straight grooves, or a flexible or jointed sheet in curved grooves, and so arranged as to be moved vertically to expose all the names or to conceal one after another as the stations are passed. This latter arrangement 75 is shown in the drawings, the shield being worked by the knob D, and held by friction or locked at the desired points by the bolts D'. If preferred, sliding independent shields, inserted sidewise, may be substituted and 80 employed to cover any or all of the names, as occasion requires.

The shield may be worked from within the car, as the train approaches the station, by means of a knob H, connecting with it at a 85 point convenient for the brakeman, and a gage, I, may denote the number of plates exposed. (See Fig. 2.)

I claim as my invention—

1. As a permanent attachment to the exterior of a railroad-car, and in combination therewith, a suitable frame, inclosed station-plate or series of station-plates having the

names of the several stopping-places arranged in the order in which they will be reached, together with a movable shield adapted to be successively closed over the front of said plates 5 as the train proceeds, all substantially as described.

2. In a station-indicator attached to the exterior of a car, as described, the combination of the indicator-case, inclosed station-plates,

movable shield for successively covering said 10 plates, and means for operating the shield from within the car, substantially as set forth.

In testimony whereof I hereto affix my signature in presence of two witnesses.

WALTER J. PETTINGELL.
